CLAIM

The ornamental design for a cat litter house, as shown and described.

DESCRIPTION

FIG. 1 is a front perspective view of a cat litter house showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof;

FIG. 9 is an enlarged detail view taken from portion 9 of FIG. 1;

FIG. 10 is an enlarged detail view taken from portion 10 of FIG. 1; and,

FIG. 11 is an enlarged detail view taken from portion 11 of FIG. 1.

The evenly-dashed broken lines show portions of the cat litter house that form no part of the claimed design. The dot-dash broken lines depict the boundary of the enlarged views and form no part of the claimed design.

1 Claim, 11 Drawing Sheets
